DERMATOME

John D. Reese, Philadelphia, Pa.

Application September 25, 1945, Serial No. 618,523

29 Claims. (Cl. 128—305)

1

This invention relates to surgery, more particularly to skin grafting, and has for an object to provide an improved dermatome for cutting a skin graft.

Another object of the invention is to provide, in a dermatome of the type comprising a body member having a convex working face and a knife supported by the body member for cutting movement parallel to said convex face and at a predetermined distance therefrom, improved means for adjusting the spacing of the knife with respect to the convex working face.

While the improvements of the present invention may be used with almost any type of dermatome, they are particularly applicable to the type having a convex working face, as illustrated by United States Letters Patent No. 2,283,709, granted July 7, 1942, to G. J. Hood, and by applicant's prior Patent No. 2,366,054, granted December 26, 1944.

In using dermatomes of this type, it has been the practice to apply a coat of liquid adhesive or cement to the convex working face, and a similar coat to the skin of the donor area, or to stick to the dermatome working face a rubber sheet of proper size and shape, coated on both sides with a soft adhesive rubber compound. The convex face was then rolled on the adhesive-coated donor area, and simultaneously a knife, supported by the dermatome for reciprocatory and oscillatory movement parallel to the convex face, was given a cutting motion to separate the graft from the donor area, as the skin thereof was raised by the adhesive during the rolling action. After completion of the cutting operation, the graft was removed from the adhesive, applied to the injured area, and retained in position thereon by sutures or clamps.

Where the convex surface was coated with adhesive or cement, the difficulty was frequently encountered that the coating pulled away from the surface in spots, with the result that at such spots the skin was not raised, and the knife cut holes in the graft. The same difficulty arose where the rubber sheet, coated on both sides with rubber adhesive, was relied upon, as the adhesive retaining the rubber sheet on the dermatome convex face likewise tended to pull away in spots, resulting in the cutting of holes in the graft.

Also, it has been proposed to retain a rubber sheet, having adhesive on only its outer skin-engaging face, in position on the convex working face of a dermatome, solely by suction. Here again, difficulty may be encountered in obtaining a satisfactory graft, mainly because of fail-

2

ure of the graft-receiving rubber sheet to remain tight against the dermatome, due to unreliability of such suction apparatus. Whether the rubber sheet is held in place by adhesive or by suction, it is subject to wrinkling or partial separation from the dermatome because of non-uniformity of securing action.

Therefore, another object of the invention is to provide, in a dermatome, means for positively securing a graft-receiving member against a convex working face, with the contact pressure between the member and the face uniform at all points therebetween.

A further object of the invention is to provide 15 a dermatome having means for mechanically securing against its working face, a graft-receiving member of flexible material.

Yet another object of the invention is to provide 20 securing to its working face, a graft-receiving member of flexible material, together with means for drawing said member taut against said working face.

Another object of the invention is to provide 25 a dermatome constructed of a combination of such materials as will result in uniform expansion and contraction of all parts thereof when the dermatome is sterilized at high temperatures.

These and other objects are effected by the invention as will be apparent from the following 30 description and claims taken in accordance with the accompanying drawings, forming a part of this application, in which:

Fig. 1 is a front elevational view, partially in 35 section, of a dermatome embodying features of the present invention;

Fig. 2 is a vertical sectional view, taken along the line II—II of Fig. 1, looking in the direction indicated by the arrows;

Fig. 3 is a plan view of a graft-receiving or 40 graft-transfer member, adapted for use with the dermatome of the present invention, portions thereof being broken away at one corner to more clearly illustrate the laminated construction;

Fig. 4 is a view similar to Fig. 3, showing 45 a modified graft-receiving member;

Fig. 5 is a fragmentary sectional view of the 50 injured area of a patient's body, showing a skin graft retained thereon;

Fig. 6 is a front elevational view of an improved dermatome, constructed in accordance with the present invention;

Fig. 20 is a view similar to Fig. 17, but showing the graft-transfer member in final tightened position.

Fig. 21 is a plan view of the wrench or tool used to adjust the ratchet and the cam;

Fig. 22 is a transverse sectional view of a modified form of dermatome; and

Fig. 23 is a side elevational view, taken along the line XXIII—XXIII of Fig. 22, looking in the direction indicated by the arrows, the shaft and associated post structure being omitted.

Referring now to the drawings more in detail, particularly to Sheet 1, Figs. 1, to 5, wherein the principles of the present invention are illustrated broadly, the reference character 10 indicates, in its entirety, a dermatome comprising a body portion 11 in the form of a semi-cylindrical drum made of a spaced pair of semi-cylindrical side walls 12, joined by a curved end wall 13 having an outer convex working face 14. The side walls 12 carry a bearing 16 bridging the space between the side walls and positioned so that its longitudinal axis coincides with the axis of generation of the convex working face 14.

A shaft 17 is journaled in the bearing 16 for both rotary and reciprocatory movement relative to the body member, and carries at its terminal portions a pair of posts 18, which extend radially relative to the convex working face 14, in parallel, spaced-apart relation, with the spacing therebetween considerably greater than the width of the body member or drum 11, to provide for reciprocatory movement of the shaft 17 and posts 18 relative to said body member.

The posts may be retained on the shaft terminal portions by a pair of knurled finger nuts 19, although, preferably, a handle or finger piece 21 is used in place of one of the knurled nuts 19 to serve as a more suitable grip for the hand of the operator when reciprocating the shaft.

A blade-supporting bar 22 is carried by the outer ends 23 of the posts, and is provided with

10

5

a pair of lugs 24, slidably received in bores 26, formed in the post ends 23. A knife 27 is adapted

to be supported on the bar 22, with its cutting

edge 28 in parallel relation to the convex sur-

face 14 of the drum.

A pair of rods 31, rotatable in bores 32 of the posts, have threaded connections, at their inner ends 33, with threaded bores in the lugs 24. The outer ends of the rods 31 carry knurled finger pieces 34, by which the rods may be rotated to move the lugs longitudinally of the bores 26 in which they are positioned, inward movement of the lugs serving to draw the bar 22 towards the ends of the posts to securely clamp the knife 27 thereagainst.

Adjustment of the spacing of the knife with respect to the convex working face 14 is obtained by inserting between the knife and the post ends 23, shims 36 of the desired thickness.

The structure so far described constitutes, of itself, no part of the present invention, being already known to the art, and a more complete description of the details of construction may be obtained from applicant's prior patent, previously referred to.

20 The present invention provides a dermatome adapted to make use of a skin graft-receiving or graft-transfer member 40, in the form of a flexible sheet. As best shown in Figs. 2 and 3, the graft-transfer member 40 comprises an intermediate strip of fabric 41, which is so disposed with respect to the sheet that the warp ends extend lengthwise; thereby rendering the flexible sheet substantially inextensible in a lengthwise direction, the fabric having permanently secured to the lower face thereof, as viewed in Fig. 3, a coating or layer 42 of rubber, whose surface, which is away from the fabric, is dry and smooth, for a purpose to be hereinafter set forth.

25 40 On the upper face of the fabric 41 is permanently secured a layer or coating 43 of rubber, whose surface which is away from the fabric is of an adhesive character. To protect the adhesive surface, the latter is covered with a strip of protective material 44, preferably of cloth which has been starched, varnished or otherwise processed.

30 50 The graft-transfer member 40 is of a width slightly less than the distance between the body member side walls 12, and of a length materially greater than the developed length of the convex working face 14 of the body member, the excess length constituting securing portions B, at each end of the strip, and the remaining intermediate section constituting a skin-contacting portion A.

35 55 In use, the graft-transfer member 40 is applied to the body member of the dermatome, with the smooth inner surface of the rubber layer 42 against the convex working face of the body member, the intermediate skin-contacting portion A terminating adjacent the ends of the convex face. The securing portions B of the member 40 are drawn over the ends of the convex wall 13 and the protective layer 44 may first be removed therefrom, although this is not generally necessary.

40 50 To permit ready removal of this protective layer 44 from the end securing portion B, without disturbing the protective layer covering the intermediate skin-contacting portion A, the protective layer 44 is provided with a break at the line where the portion A terminates and the portion B commences, as at 46 in Fig. 3. If desired, the protective layer may be merely weak-

ened by a cut or by a row of serrations or perforations, indicated at 47 in Fig. 4.

Where the member 40 is attached without removal of the protective layer 44 from the attaching portions B, the breaks 46, or cuts or perforations 47, provide the "give" in the layer 44 which is necessary to permit the strip 41 to be drawn taut over the convex face of the body member.

In accordance with the present invention, the dermatome is provided with means for mechanically securing the graft-transfer member thereto. In its broadest form, as illustrated in Figs. 1 to 5, the dermatome side walls 12 are provided, adjacent one end of the curved wall 13, with a pair of slots 50, which are inclined towards said one end of the curved wall, relative to the inner surface of that wall. A knurled bar or roller 51 has its terminal portions mounted in the slots 50, for free rolling or sliding movement therein. The adjacent securing portion B of the graft-transfer member is positioned in the space between the bar 51 and the inner surface of the curved wall 13, any pull on the securing portion B in an upward direction, as viewed in Fig. 2, resulting in wedging of the bar 51 against the portion B, thereby preventing withdrawal of the latter.

The securing portion B at the opposite end of the graft-transfer member may be held by a quick-release latch or dog 52, pivoted at 53 to the side walls 12, and having a grip 54 and handle 56, as well as a stop 57. The entire latch or dog may be of well known construction, such as is frequently used in buckles.

In order to hold the intermediate portion A of the graft-transfer member taut against the convex working face of the dermatome, there is provided a tightening rod 58, pivotally mounted in opposed openings in the side walls 12, and formed with a cam surface eccentric relative to its axis of rotation. One end of the rod 58 may extend beyond the corresponding side wall 12, and carry a knurled finger piece 59, by which the rod may be rotated to cause the cam surface thereof to raise the graft-transfer member where it passes thereover, to draw the member taut. In order to distribute uniformly throughout the length of the graft-transfer member the stress to which the latter is subjected when drawn taut by the cam rod 58, the inner convex-face-engaging surface of the graft-transfer member is made smooth and dry, so that it may slip easily on said convex face.

Preferably, the protective layer 44 is left on the intermediate skin-contacting portion A until such time as the graft is to be cut, when the layer 44 is removed and the graft cut in a manner obvious to those familiar with dermatomes of this type.

Briefly, the dermatome is operated as follows in the cutting of a graft: The dermatome is applied to the body with one end of the intermediate skin-contacting portion A pressed against the skin of the donor area, the protective layer 44 having been removed from the portion A. The body member or drum is then rolled on the donor's body with the adhesive layer 43 progressively raising the skin. Simultaneously with the rolling of the body member, and consequent raising of the skin, the knife is reciprocated relative to the body member and the skin to cut the latter in the form of a graft. Upon completion of the cutting, the entire graft-transfer member is removed from the dermatome, and the graft

applied to the injured area, preferably without removal from the graft-transfer member. It will be apparent that by leaving the graft on the graft-transfer member, shrinkage or wrinkling of the graft is prevented.

Further, after the graft and its transfer member have been applied to the injured area, the transfer member may be used to retain the graft in place, thereby eliminating the use of sutures or clamps. Fig. 5 illustrates a graft 60 applied to the injured area 61 of a patient's body 62, the graft 60 being retained in place and protected by the graft-transfer member, to which the graft is still attached. Strips 63 of adhesive tape may be used to retain the graft-transfer member in place on the patient's body, as illustrated.

An important advantage of the use of a tautly drawn graft-receiving or transfer member, such as herein described, and originally disclosed in my copending application, Serial No. 583,983, filed March 21, 1945, is that a much thinner graft can be cut than would be possible if the graft had to be removed from the adhesive surface prior to being applied to the injured area. By use of a taut graft-transfer member, a graft of two-thousandths of an inch thickness may be cut and applied to the injured area without injury to the graft, where, such a thin graft would be torn or otherwise damaged if it were removed from the adhesive coating prior to being applied to the injured area, and even if successfully removed would be clinically unmanageable.

Where the graft-receiving member is secured to the dermatome working face by adhesion, suction, or any means other than mechanical, the degree of surface contact, or the force tending to hold the member to the working face, will vary at different areas of the meeting surfaces, resulting in cutting a graft of non-uniform thickness. If it is attempted to cut a graft as thin as two-thousandths of an inch, the graft is likely to be too thin in spots where the surface contact is slight, or even to have holes therethrough.

In the construction shown in Fig. 4, an opening 66 is cut in the protective layer 44, by the operator, which opening is of the shape and size of the graft to be cut, the layer 44 overlying the remainder of the intermediate portion A serving to mask the adhesive layer 43, so that the donor area skin will adhere to the graft-transfer member only through the opening 66.

The mechanism for securing the graft-transfer member to the dermatome and for drawing it taut against the convex working face, illustrated in Figs. 1 and 2, is somewhat elementary and only for the purpose of illustrating the principle of the present invention. For a detailed disclosure of what is considered a preferred embodiment of the invention, reference is now made to Figs. 6 to 21, inclusive, on sheets 2, 3 and 4 of the drawings.

Preferred construction of dermatome (Figs. 6, 7, 10 and 11)

65 The above-mentioned figures disclose a dermatome, indicated in its entirety by the reference character 75, and having a drum or body member 76 comprised by a pair of semi-cylindrical side walls 77 and 78, maintained in parallel spaced-apart relation by a curved bottom wall 79 having a convex working face 81. Preferably, the side walls 77 and 78 and the bottom wall 79 are formed as a unitary casting.

A cylindrical handle 82 bridges the space between a pair of ears 83 projecting beyond the

straight edges of the side walls 77 and 78, the longitudinal axis of the handle coinciding with the axis of generation of the convex working surface 81. Preferably, the handle 82 is knurled, as at 84, to provide an improved grip for the operator's hand.

The handle 82 is hollow, as at 85, for passage therethrough of a shaft 86, which is journaled in hardened steel bushings 87, pressed into counter-bores 88 at the ends of the handle 82. Thus, the bushings 87 not only serve as bearings for the shaft 86, but also retain the handle 82 in position with respect to the ears 83 of the side walls 77-78. Preferably, the bushings 87 are provided with terminal flanges 89, abutting the side wall ears 83 and prevented from rotating relative thereto by pins 91 extending through the flanges 89 and the ears 83.

Post adjustment mechanism (Figs. 6, 7, 8 and 11)

The shaft 86 has one of its terminal portions 92, of reduced diameter, permanently secured in the mating opening 93 of an adjustment body 94, by a pin 95 extending through the adjustment body and the terminal portion. The shaft's other terminal portion 96 is threadedly received in the mating opening 97 of an adjustment body 98 and the latter is retained in a position of parallelism with respect to the other adjustment body 94 by the set screw 99. The spacing of the adjustment bodies 94 and 98 on the shaft 86 is materially greater than the width of the body member 76, with the result that limited reciprocatory movement of the shaft relative to the body member is obtainable.

Both of the adjustment bodies are provided with axial bores 101, whose axes extend normal to the axis of the shaft 86 and parallel to each other. An adjustment bushing 102 is rotatably mounted in each bore 101, and is prevented from longitudinal movement therein by a flange 103, abutting the lower edge of the adjustment body, as at 104, and by an adjustment knob 105, secured on the upwardly-projecting end 106 of the adjustment bushing by a pin 107. The lower edge of the adjustment knob 105 abuts the upper edge of the adjustment body, as at 108. Preferably, the adjustment knobs 105 are provided with knurled edges, as at 109.

The adjustment bushings 102 have internally threaded bores 111 for reception of correspondingly threaded arms 112. Preferably, these threads are relatively fine, for example, forty threads to the inch, to secure a high degree of accuracy in adjusting the arms 112 by rotation of the adjustment knobs 105 and their associated bushings 102, while the arms 112 are prevented from rotating.

Each arm 112 terminates in a head 113 of a length sufficient to project beyond the convex surface 81 of the drum or body member 76. The bottom of each head 113 is a flat surface 114, lying in a plane disposed at an angle (preferably 120 degrees) to the longitudinal axis of the arm 112. One side of the head 113 is provided with a right-angle notch 115, whose surface 116 is parallel to the surface 114. A passage 117, of circular cross section, extends through the head 113 at right angles to the parallel surfaces 114 and 116, and is adapted to rotatably receive the body 118 of the blade bar lock nut 119.

Blade supporting mechanism (Figs. 8, 9 and 10)

The blade bar lock nut body 118 has a two-diameter bore, the smaller diameter 121 of the bore being threaded, and the larger diameter 122

being smooth-walled. A guide pin 123 is adapted for reception in the two-diameter bore 121-122, the smooth guiding portion 124 of the pin fitting closely in the bore 122, and the threaded tip 125 of the guide pin being threadedly received in the bore 121 of the lock nut body 118.

A pair of the guide pins 123 extend perpendicularly from the upper surface 126 of a blade bar 127 (Fig. 9), the two guide pins being spaced apart a distance corresponding to the spacing of the two circular passages 117 in the heads 113.

A knife or blade 128 (Fig. 10), is adapted to rest on the blade bar 127, and is provided with a pair of notches 129 for reception of the pair of guide pins 123, the latter serving to position the blade longitudinally and to limit forward movement thereof. Rearward movement of the blade 128 is limited by an upwardly-projecting rib 131 at the back of the blade bar, (Figs. 8 and 9). It will be apparent that tightening of the blade bar lock nuts 119 will draw the blade bar towards the bottom surfaces 114 of the heads 113, with the blade 128 clamped therebetween.

To insure assembly of the blade bar 127 in the correct position with respect to the pair of heads 113, the blade bar is provided with a pair of upwardly-projecting pins 132, adapted to be received in mating recesses 133 in the bottom surfaces 114 of the heads 113. The longitudinal spacing and positioning of the pins 132 on the blade bar 127 corresponds to that of the guide pins 123, with the result that the pins 132 do not interfere in any way with the blade 128, as they extend freely through the notches 129 of the latter.

Adjustment for varying the thickness of grafts (Figs. 8, 9, 10 and 16)

It is preferred that variations in the thickness 40 of the grafts cut be obtained by the use of shims 134, Fig. 16, positioned between the blade and the heads 113, the shims being provided with notches 135 receiving the guide pins 123, (Figs. 8 and 13). Each dermatome is equipped with a set of pairs 45 of shims of varying thicknesses, which may be used in single pairs or in various combinations of pairs to obtain any desired spacing of the blade cutting edge 136 with respect to the dermatome convex surface 81.

Use of post adjustment mechanism (Figs. 6, 7, 8 and 11)

The adjustment obtainable with the adjustment bodies 94-98, the adjustment bushings 102 and knobs 105, and the threaded arms 112 is intended primarily for accurately aligning the cutting edge 136 of the blade 128 relative to the dermatome convex surface 81. Such adjustment may be found necessary when applying a new 60 blade or when a used blade has been resharpened.

Preferably, the adjustment knobs 105 are turned in whichever direction is necessary to space the cutting edge of the blade from the convex surface of the dermatome, an arbitrary distance of four thousandths of an inch. The adjustment mechanism is held in the desired position by a wedging lock pin 137, provided with a concavity 138 in one edge thereof, the cavity 138 receiving the side of the adjustment bushing 102, 70 (Figs. 6, 7, 8 and 11). The locking pin 137 is urged axially by a finger nut 139 threaded on the projecting terminal portion 141 thereof. Further locking of the adjustment mechanism is obtained by turning the lock nut 142 upwardly on the threaded arm 112, until the nut tightly en-

gages the lower end of the adjustment bushing 102.

Use of the graft-thickness varying mechanism (Figs. 8, 9, 10 and 16)

Once the above-described adjustment has been made for a particular blade, the adjustment is not changed until the blade has been resharpened or rehoned, or a new blade is used. To vary the thickness of grafts cut, it is only necessary to insert the desired thickness of shims between the blade and each head 113. For example, if a graft of ten thousandths of an inch thickness is desired, the operator or nurse preparing the instrument will add to the four thousandths clearance in the original adjustment by inserting shims totaling six thousandths between the blade and each of the heads 113.

The cutting-motion-imparting handle (Figs. 6 and 7)

The post 98 is provided, at the side thereof away from the drum or body member 76, with a handle 143, secured thereto in any suitable manner, for example, as by soldering or brazing, at 144. Preferably, the handle includes a depending portion 145 around which two or three of the operator's fingers may be placed for pulling the blade and its carrying mechanism, and an upwardly-projecting portion 146, against which the operator's thumb may bear for pushing the blade and its carrying mechanism. It should be noted that the thumb rest portion 146 extends upwardly at least as high as the top of the adjustment knob 105 to form a guard therefor, preventing accidental turning or misadjustment of the knob 105 by pressure of the operator's thumb thereon, were the guard not provided.

Front clamping mechanism (Figs. 12 to 15, inc.)

Reference is now made to sheet three of the drawings, particularly to Figs. 12 to 15, inclusive, for a description of the preferred mechanism for holding the graft-transfer member 40 taut against the convex working face 81 of the dermatome.

At the front, or right-hand end of the convex surface 81, as viewed in Figs. 12 to 15, inclusive, there is provided a fixed clamping block 150, extending between the side walls 77-78. The block has terminal portions, each of two diameters 151 and 152, the larger diameter portions 151 extending through mating openings 153 in the side walls and the smaller portions 152 projecting therebeyond and through washers 154, to which they are connected in a suitable manner, as by peanining, at 155.

A clamping bar 156 extends between the side walls 77-78 in parallel relation to the clamping block 150, and is mounted for limited pivotal movement on a pin 157 extending through aligned openings 158 in a pair of ears 159-160, formed integral with, and projecting rearwardly from, the clamping bar 156 near its ends, (Figs. 12 and 13). This pin 157 has its terminal portions 161 fixedly secured in the side walls 77-78, and is so disposed with respect to the clamping block 150 that when the clamping bar 156 is moved in a counterclockwise direction, as viewed in Figs. 13 and 15, its clamping face 162 engages the cooperating clamping face 163 of the clamping block 150. Preferably, the clamping faces 162 and 163 are serrated or toothed, as at 164, to provide for positive gripping of the attaching portion B at the forward end of the graft-transfer member 40

when the same is inserted in the clamping mechanism.

To facilitate movement of the clamping bar 156 to and from operative position, the ear 159 is provided with an extension or lever 165 adapted for manipulation by a finger of the operator. Once the graft-receiving member 40 is drawn taut with both ends secured, the clamping bar 156 will be wedged in clamping position, but with only the forward end of the graft-transfer member secured, and no pull applied thereto, the clamping bar might be accidentally moved from clamping position. To avoid this possibility, the extension or lever 165 is provided with a locking member or latch 166, pivoted at one end to the end of the lever 165 and adapted to swing between a locking position where it overlies the lever 165 (Fig. 12), and a releasing position (Fig. 14). When in locking position, the edge 167 of the latch is received beneath the latching pin 168, extending inwardly from the wall 77. When the latch is in releasing position, the lever 165 may be moved upward to separate the clamping faces 162-163. In order that the lever may clear the latching pin 168 during such movement, it is provided with a clearance notch or groove 169 in its outer edge. Preferably, the latch 166 is provided with an upwardly-directed flange 171 to facilitate movement thereof, by the operator, from locking position.

Rear holding and tightening ratchet mechanism (Figs. 13, 17, 18, 19, 20 and 21)

Means are provided adjacent the rear, or left end as viewed in Figs. 12 and 13, of the dermatome convex surface 81 for holding the rear end of the graft-transfer member 40 and for tightening the intermediate portion A thereof against said convex surface.

A ratchet shaft 175 extends between the dermatome side walls 77-78, in parallel relation to the rear edge 176 of the convex wall 79, and at a considerable distance below the same. One end of the ratchet shaft 175 carries a stub journal 177 rotatably mounted in a flanged bushing 178, pressed into a countersunk opening 179 in the side wall 78, (Fig. 18). The opposite end of the ratchet shaft is provided with a stub journal 181, rotatably mounted in a flanged bushing 182 disposed in a countersunk opening 183 in the side wall 77. The stub journal 181 has its terminal portion 184 extending a material distance beyond the side wall 77. The periphery of the terminal portion 184 is provided with an annular series of ratchet teeth 185, for a purpose to be explained later.

The ratchet terminal portion 184 has an axial bore 186, and a pin 187 extends diametrically thereof for engagement by the spaced jaws 188 of a wrench 189 (Fig. 21). The wrench jaws 188 are formed at the end of a nose portion 191 which is of a diameter permitting its ready insertion in the axial bore 186 of the ratchet terminal portion 184, with the pin 187 between the jaws 188. It will be apparent that rotation of the wrench 189 will correspondingly rotate the ratchet shaft 175. Preferably, the cylindrical body of the wrench is knurled, as at 193, for easy gripping by the operator. Also, the cylindrical body is provided with diametrically-opposed flat portions 194 to prevent rolling thereof when laid on a flat surface, such as a table top.

A ratchet plate 195 is secured to the outer surface of the side wall 77 by screws 196, the plate 195 having an opening 197 therethrough

11

for unrestricted passage of the ratchet terminal portion 184. The toothed portion of said ratchet terminal is of such length that a material part thereof projects beyond the ratchet plate 195 for engagement by a pawl 198, pivotally mounted on the ratchet plate 195 by the pin 199. The pawl 198 is biased to engagement with the ratchet teeth 185 by a wire spring 201 formed with a loop 202 at one end by which it is mounted on the ratchet plate by one of the screws 196, which passes through said loop. The other end 203 of the spring 201 is loosely received in an opening 204 extending through the handle 205 of the pawl 198, with the spring end 203 bearing against one wall of said opening.

The ratchet shaft 175 is slotted, as at 206, for substantially the entire distance between the dermatome side walls 77-78, for reception of the rear end of the graft-transfer member 40 (Figs. 18, 19 and 20).

Cam-tightening mechanism (Figs. 12, 13 and 17 to 20, inc.)

A cam shaft 210 is positioned between, and in parallel relation to, the rear edge 176 of the convex wall 79 and the ratchet shaft 175, with one terminal portion 211 thereof rotatably journaled in the flanged bushing 212 which is pressed into the countersunk opening 213 of the side wall 78. The other terminal portion 214 is rotatably journaled in a bushing 215, formed integral with the ratchet plate 195 and closely received in the opening 216 in the side wall 77. This terminal portion 214 is of sufficient length to project beyond the ratchet plate, and the projecting part is provided with a series of ratchet teeth 217 which preferably extend through a limited portion only of the periphery of the terminal 214, for a purpose to be hereinafter explained.

The cam shaft terminal portion has an axial bore 218, provided with a pin 219 extending diametrically thereof, the bore 218 and pin 219 corresponding in structure and function to the bore 186 and pin 187 of the ratchet shaft 175, with the result that the same wrench 189 serves to rotate both the ratchet shaft and the cam shaft.

A pawl 221 is urged into contact with the ratchet teeth 217 of the cam shaft by the same spring 201 which exerts a biasing effect on the previously-described pawl 198. The pawl 221 is pivotally mounted on the ratchet plate 195 by a pin 222, with a pair of spaced bearing portions 223 and 224 contacting an intermediate section of the wire spring 201 (Fig. 17).

The cam shaft periphery 225 is eccentric relative to the journals thereof, with the result that as the shaft is rotated, the line 226 on the periphery 225 which is farthest from the center of rotation 227, moves in the path indicated by the dotted line C, in Fig. 17.

Operation of ratchet and cam securing and tightening mechanism (Figs. 17 to 21, inc.)

After the forward end of the graft-transfer member 40 has been secured by the clamping mechanism at the front of the dermatome, the rearward end of the transfer member is brought around the outside of the convex surface 81, and over the rear edge 176 of the convex wall 79 and the cam shaft 210. The free rear end of the transfer member is directed upwardly through the slot 206 in the ratchet shaft 175, with a terminal portion 226 extending therebeyond (Fig. 19), and adapted to be doubled back and overlapped when the ratchet shaft is rotated by the

15
20
25
30
35
40
45
50
55
60

12

wrench (Fig. 20). While the ratchet shaft is being turned to draw the graft-transfer member taut, the cam shaft 210 is in its inactive position, as shown in Fig. 19.

Inasmuch as it might be difficult for non-mechanically-minded operators to accurately determine by eye when the cam shaft is in its inactive position, the series of ratchet teeth 217 thereof is interrupted by a smooth portion 227. Before the graft-transfer member is inserted in the slot of the ratchet shaft, the wrench is applied to the cam shaft and the latter rotated until the smooth portion 227 passes beneath the pawl 221 and the latter engages the first tooth 217. This action will result in a quiet turning of the cam shaft, followed by a click as the pawl drops into the notch beside the first tooth, this first click indicating to the operator that the cam is in inactive position. This signal will be discernible to the operator both by ear and by feel.

The tightening action of the ratchet shaft will frequently be insufficient to draw the graft-transfer member as taut against the convex surface as is desired, due to the fact that the tightening action of the shaft is limited to increments corresponding to the angular movement between adjacent teeth on the ratchet shaft. For example, if a tightening action corresponding to five and a half teeth was required, there would be no way to hold the last half-tooth of motion.

This final tightening, corresponding to a fraction of a tooth on the ratchet shaft, is obtained by rotation of the cam shaft from inactive position towards a position of maximum action or eccentricity, i. e. from the position of Fig. 19 to that of Fig. 20. Any additional tightening obtained by rotation of the cam shaft is retained by engagement of the pawl 221 with the teeth 217. It will be noted that not only are the teeth of the cam shaft closer pitched than those of the ratchet shaft, but a full half-turn of the cam from minimum to maximum eccentricity produces much less total movement of the graft-transfer member than a full turn of the ratchet shaft. Therefore, tightening action over several teeth on the cam shaft is required to equal that of one tooth on the ratchet shaft.

Release of graft-transfer member (Figs. 12 to 15 and 17)

When the graft-cutting operation has been completed, and it is desired to remove the graft-transfer member 40 from the dermatome, the front end of the transfer member is released by swinging the latch 166 from the locking position of Fig. 12 to the released position of Fig. 14, then lifting the lever 165 from its position, as shown in Fig. 14, to that shown in Fig. 15, whereupon the forward end of the transfer member will slip from between the clamping block and clamping bar due to the tension it was under prior to release.

65
60
65
70
75
80
85
90
95

The rearward end of the transfer member is released simply by pulling thereon lightly, while pressing on the handle 205 of the pawl 198 to disengage the latter from the teeth 185 of the ratchet shaft, the shaft rotating until the transfer member is unwound therefrom and slips out of the slot 206.

Relieved edges of drum convex surface (Figs. 6, 7, 12 and 14)

Where the outer convex surface of the drum or body member extends for the full width of the body member, as in the construction illustrated in Figs. 1 and 2, there will be edge portions of

said surface which will not be covered by the graft-transfer member, as the width of the latter is limited to slightly less than the spacing of the inner surfaces of the side walls. In cutting a graft, the adhesive or cement which is applied to the patient's donor area skin, may adhere to the exposed edge portions of the convex surface, in which event the blade will cut a graft including the areas of the exposed edge portions, and the corresponding edge portions of the graft so cut will be so much thicker than the rest of the graft as to constitute beads, the blade cutting below the patient's skin and into the fatty tissue.

To avoid this danger, the dermatome of Figs. 6 to 21, inclusive, has the side edges of its convex surface 81 cut away, or relieved, as at 230, so that the remaining convexed surface is of a width only slightly greater than that of the graft-transfer member 40 (preferably, about one-thirty-second of an inch greater).

Measuring indicia (Figs. 13 and 15)

It is preferred that a dermatome for cutting grafts from adults have a convex surface approximately four inches wide and eight inches long, so that a graft of thirty-two square inches may be obtained at one cutting. Frequently, a cut of less than thirty-two square inches is desired, and difficulty may be encountered in determining accurately how far around the drum to cut to obtain the desired area. The present invention meets this difficulty by providing, at the semi-cylindrical edge of one or both of the side plates 77 and 78, a series of graduations or indicia 233, preferably expressed in inches and fractions thereof, and starting at the front, or right-hand edge, as viewed in Figs. 13 and 15.

Narrow drum dermatome (Figs. 22 and 23)

While, as previously indicated, a drum having an effective width of approximately four inches is preferred for use with adult patients, in the case of children and some types of adult work a narrower drum is preferable due to limited donor areas available. A drum having an effective width of two and a half inches is desirable in many instances. However, it has heretofore been thought that a drum of less than four inches width was impractical, due to the space necessary between the drum side walls for the operator's fingers in gripping the handle of the dermatome.

In Figs. 22 and 23 there is illustrated a dermatome whose drum has an effective width of only about two and a half inches, yet which provides ample space for the operator's fingers. This dermatome is identical to that previously described in connection with Figs. 6 to 21, inclusive, except for the drum 250 and the length of the shaft 86.

The drum or body member 250 comprises a central web 251, preferably cast integral with the convex wall 252, the handle core 253 and the pair of low side walls 254 and 255. The handle core 253 is axially bored, as at 256, and counter-bored at each end, as at 257, for reception of hardened steel bushings 258 in which the shaft 86 slides and rotates. Knurled sleeves 259 are pressed on the handle core 253 from opposite ends thereof, and abut the upper edge of the central web 251. As indicated in Fig. 23, the central web extends for only about the central third of the front-to-rear overall dimension of the drum, as viewed in Fig. 23, with the result that there is no interference with the transversely-extending

clamping block and bar, and with the ratchet and cam shafts.

Preferably, the central web 251 is provided with flanges 263 at its front and rear edges, which flanges are integral with the convex wall 252 and extend laterally a short distance from the central web 25, to further stiffen the latter.

The inner edges 260 of the side walls 254 and 255 are spaced radially from the handle a distance amply sufficient for the operator's fingers when the handle 259 is gripped.

Preferably, all of the modifications of dermatomes herein shown and described are provided with aligned openings in the side walls near the convex wall and substantially midway of the length of the latter, as at 55 in Figs. 1 and 2, at 30 in Figs. 6 to 21, inclusive, and at 264 in Figs. 22 and 23. These openings are used in positioning the dermatomes on stands or supports during adjustment of the various mechanisms, both prior to, and following, the cutting of grafts. If desired, these openings may be provided with bushings, as at 90 in Figs. 6 to 21, inclusive, and at 262 in Figs. 22 and 23.

In the preferred embodiments, the drums or body members are made of cast brass, and all the remaining parts which are permanently associated therewith are manufactured of stainless steel. The combination of these two metals has the advantage that their coefficients of expansion are so nearly alike that no binding, misalignment or warping of associated parts occurs when the instrument is subjected to the relatively high temperatures encountered when sterilizing the same.

While the invention has been shown in several forms, it will be understood that it is not so limited, but is susceptible of various changes and modifications without departing from the spirit thereof.

This application is a continuation-in-part of applicant's copending application for Skin grafting method and apparatus, Serial No. 583,983, filed March 21, 1945.

What is claimed is:

1. A dermatome including a body member comprising a pair of approximately semi-cylindrical spaced parallel side walls joined along their convex edges by a curved bottom wall having a convex outer surface, and means for supporting a graft-cutting blade from said body member for cutting movements in parallel relation to the convex outer surface, the width of said convex surface being approximately the same as the space between said side walls.

2. A dermatome including a body member comprising a pair of spaced parallel side walls joined by a curved bottom wall having a convex outer surface, and means adapted to support a graft-cutting blade from said body member for cutting movement parallel to said convex outer surface, said curved bottom wall having its convex outer surface at its side edges relieved an amount approximately equal to the thickness of the side walls.

3. A dermatome comprising a body member including a pair of semi-cylindrical side walls disposed in parallel spaced-apart relation and a bottom wall joining said side walls at their convex edges and having a convex outer surface; means adapted to support a graft-cutting blade from the body member for cutting movement parallel to said convex outer surface, and means for retaining a graft-transfer member against said convex outer surface with a portion of said transfer

15

member disposed between said spaced side walls, the effective width of said convex outer surface corresponding approximately to the spacing of said side walls.

4. A dermatome comprising a body member having a convex outer surface, means adapted to support a graft-cutting blade from said body member for cutting movement parallel to said convex outer surface, means for securing one end of a flexible graft-transfer member to the dermatome, means for securing the other end of graft-transfer member to the dermatome with the intermediate portion of said transfer member against said convex outer surface and for pulling said transfer member in increments to tighten said intermediate portion, and cam means for tightening said transfer member a portion of one of said increments.

5. In a dermatome including a body member having a convex surface against which a flexible graft-transfer member is adapted to be held taut, means carried by the body member and adapted to hold one end of the graft-transfer member, means adjustable in predetermined increments and adapted to tighten and hold the other end of said graft-transfer member with the intermediate portion of said transfer member engaging the convex surface of the body member, and means for further tightening said transfer member in fractions of said predetermined increments.

6. In a dermatome including a body member having a convex surface against which a flexible graft-transfer member is adapted to be held taut, means for holding each end of said transfer member to the body member, the means for holding one of said ends comprising a pair of clamping members, one of which is movable toward and away from the other into and out of clamping relation, and means by which such movement may be imparted to the movable clamping member.

7. Structure as specified in claim 6, including means for releasably locking the clamping members in clamping relation.

8. In a dermatome including a body member having a convex surface against which a flexible graft-transfer member is adapted to be held taut; a first means for holding one end of said graft-transfer member to said body member; and a second means for holding the other end of said graft-transfer member to said body member, said second means comprising a rotatable shaft, means for securing said other end of the graft-transfer member thereto, and means for applying rotary motion to said shaft to draw said graft-transfer member taut against said body member convex surface.

9. Structure as specified in claim 8, including means for retaining said shaft in rotated position with the graft-transfer member drawn taut thereby.

10. In a dermatome including a body member having a convex surface against which a flexible graft-transfer member is adapted to be held taut; first means carried by the body member for holding one end of said graft-transfer member thereto; a shaft rotatably journaled on said body member; means for securing the other end of said graft-transfer member to said shaft with the intermediate portion of said transfer member disposed against said body member convex surface; and means for transmitting rotary motion to said shaft, whereby said graft-transfer

16

member is drawn taut against said convex surface.

5 11. Structure as specified in claim 10, including cooperating ratchet and pawl mechanisms associated with said shaft and body member for retaining said shaft in rotated position with the graft-transfer member held taut.

10 12. In a dermatome including a body member having a convex surface against which a flexible graft-transfer member is adapted to be held taut; clamping means carried by the body member for securing one end of the graft-transfer member thereto; a shaft rotatably supported by said body member; means for securing the other end of said graft-transfer member to said shaft with the intermediate portion of said graft-transfer member positioned against said body member convex surface; a ratchet carried by said shaft; a pawl having a stationary pivotal support relative to said body member and adapted to cooperate with said ratchet to retain said shaft in rotated position with said graft-transfer member taut; and a second shaft eccentrically journaled in said body member and adapted, when rotated, to bear with gradually-increasing pressure against an unsupported portion of the graft-transfer member intermediate its points of securing by the clamping means and the first-mentioned shaft.

15 13. In a dermatome including a body member having a convex surface against which a flexible graft-transfer member is adapted to be held taut; first and second securing devices carried by said body member for fastening opposite terminal portions of the graft-transfer member to the body member, one of said securing devices including means for drawing said graft-transfer member taut against the body member convex surface.

20 14. Structure as specified in claim 13, including means adapted to engage the graft-transfer member intermediate its secured terminal portions, said means being adjustable to increase the tautness of said graft-transfer member beyond 25 that provided by the tautness-producing means of said one of the securing devices.

25 15. A dermatome comprising a body member having a pair of side walls joined at one edge by a curved bottom wall having a convex outer surface, bearing structure carried by said pair of side walls, a shaft journaled in said bearing structure for rotary and reciprocatory movement relative to said body member about and along an axis coinciding with the axis of generation of the 30 convex outer surface, a pair of posts carried by the terminal portions of said shaft and extending radially of the latter in parallel relation at opposite sides of the body member, a head at the outer free end of each of said posts, blade-supporting means carried by said heads and bridging the space therebetween, means for adjusting said blade-supporting means toward and away from the heads, and means for adjusting said heads toward and away from the shaft.

35 16. A dermatome comprising a body member having a convex outer surface, bearing structure carried by said body member, a shaft journaled in said bearing structure for rotary and reciprocatory movement therein relative to said body member about and along an axis coinciding with the axis of generation of the body member convex outer surface, a frame carried by said shaft and including a member adapted to support a blade with its cutting edge in close proximity to said convex outer surface, first adjusting means

17

for obtaining parallelism between the cutting edge of a blade supported by said frame and said convex outer surface, and second adjusting means for varying the spacing of said blade-cutting edge with respect to said convex outer surface.

17. A dermatome comprising a body member having a convex outer surface; bearing structure carried by said body member; a shaft journaled in said bearing structure for rotary and reciprocatory movement; a frame carried by said shaft and including a pair of spaced, parallel posts at opposite sides of the body member and a blade-supporting member carried by the free outer ends of said posts and adapted for movement parallel to and at a predetermined distance from said convex outer surface, each of said posts including a threaded arm, a rotatable adjusting sleeve threaded on said arm, means for preventing rotation of said arm during rotation of said adjusting sleeve, whereby rotation of said adjusting sleeve will vary the effective length of the post, and a head carried by said arm and to which the blade-supporting member is secured, and means carried by each of said heads for securing said blade-supporting member thereto, said last-mentioned means urging the blade-supporting member towards the heads to clamp a blade between said member and said heads, whereby the predetermined spacing of said blade-supporting member with respect to the convex outer surface may be accurately varied by the insertion of shims of the desired thickness between the blade and the heads.

18. For use in a dermatome having a pair of shafts provided with ratchet teeth; a pawl assembly comprising a supporting plate having a pair of openings therethrough for free passage of the ratchet-toothed portions of said pair of shafts, a pair of pawls pivotally mounted on said supporting plate in position to engage the shaft ratchet teeth when said shaft toothed portions extend through said openings, and a spring mounted on said supporting plate for tensioned engagement with both of said pawls and adapted to urge the latter into mating relation with the shaft ratchet teeth.

19. Apparatus of the character described comprising a body member having a convex surface; a shaft supported by said body member for rotary and reciprocatory movement relative thereto; a pair of posts carried by the terminal portions of said shaft at opposite sides of the body member and in parallel relation; means for adjusting the length of each post radially of the shaft, said means including an adjusting knob at the upper end of each post; means supporting a blade from the lower ends of the pair of posts with the cutting edge thereof disposed in close proximity, and parallel to, the convex surface of the body member; and a handle carried by one of said posts and adapted to be gripped by the operator of the apparatus to impart the desired rotary and reciprocatory motion to the shaft, posts and blade relative to the body member and its convex surface, said handle including a first portion adapted to be engaged by the operator's fingers and a second portion adapted to be engaged by the operator's thumb, said second portion being disposed between the adjusting knob and the operator's thumb when the handle is gripped, whereby accidental turning of said adjusting knob by contact with the operator's thumb, is prevented.

20. In a dermatome; a body member comprising a curved wall of uniform width having a

18

convex outer surface; a pair of side walls extending from the side edges of said curved wall radially inward relative to the axis of generation of said convex outer surface; a central wall parallel to, and substantially midway of, said side walls and extending radially inward from the inner surface of the curved wall a material distance beyond said axis of generation of the convex outer surface; a handle carried by said central wall and extending transversely relative to said central and side walls and being spaced radially from the inner edges of the latter; a shaft journaled in said handle for rotary and reciprocatory motion relative to said body member, the longitudinal axis of said shaft coinciding with said axis of generation of the convex outer surface; and means for supporting a blade from said shaft with its cutting edge adjacent and parallel to said convex outer surface.

21. In a dermatome; a body member comprising a curved bottom wall having a convex outer surface and parallel side edges, a central wall extending upwardly from the bottom wall substantially midway of, and parallel to, the side edges of the curved bottom wall, and a handle carried by said central wall; a shaft journaled in said handle for rotary and reciprocatory movement relative to said body member; and means carried by said shaft for supporting a blade with its cutting edges adjacent and parallel to said convex outer surface.

22. Structure as specified in claim 21, including laterally-extending webs connecting the central wall and the curved bottom wall and bracing the former relative to the latter.

23. In a dermatome; a body member comprising a curved bottom wall having a convex outer surface against which a flexible graft-transfer member is adapted to be held, a pair of parallel side walls extending upwardly from the side edges of said bottom wall towards the axis of generation of said convex outer surface, a central wall parallel to, and midway of, said pair of side walls, and a handle carried by said central wall and extending transversely thereof; a shaft journaled in said handle for rotary and reciprocatory movement relative to the body member, the axis of rotation of said shaft coinciding with the axis of generation of said convex outer surface; and said handle being spaced radially from the upper edge of said side walls; means carried by said shaft for supporting a blade with its cutting edge parallel to, and spaced slightly from, said convex outer surface; first graft-transfer member securing means carried by said side walls and bridging the space therebetween near one end of the curved bottom wall; and second graft-transfer member securing means carried by said side walls and bridging the space therebetween near the other end of said curved bottom wall.

24. The method of transferring a skin graft from a donor area to an injured area which comprises; temporarily retaining a flexible, adhesive-coated graft-transfer member taut against a convex surface with the adhesive coating exposed; rolling the convex surface, with the graft-transfer member taut thereon, over the donor area, thereby causing the skin of the donor area progressively to adhere to said graft-transfer member through the action of said adhesive coating, said rolling action thereby lifting said skin; cutting the lifted skin simultaneously with the rolling action, while maintaining the line of sev-

19

erance a predetermined distance from the graft-transfer member; removing the graft-transfer member, with the graft thereon, from the convex surface; positioning the graft on the injured area without removing it from the graft-transfer member; and retaining the graft in position by means of the graft-transfer member.

25. In a dermatome, the combination of a body member having a working face, means for supporting a cutting member for cutting movement parallel to said working face and at a predetermined distance therefrom, and means for mechanically securing taut against said working face a flexible graft-receiving member.

26. In a dermatome, the combination of a body member having a convex working face, means adapted to support a knife for cutting movement parallel to said working face and at a predetermined distance therefrom, means for securing a graft-receiving member on said working face, and means for drawing said graft-receiving member taut.

27. A dermatome comprising a body member having a convex working face; a pair of parallel, spaced-apart posts at opposite sides of the body member and extending radially with respect to said convex face; a blade-supporting bar carried by the posts at one end of the latter and bridging the space therebetween; means pivotally and slidably supporting the posts at their other ends from the body member for movement of the bar parallel to, and at a predetermined distance from the convex face; and means for mechanically

5
10
15

20
25

20

retaining a flexible graft-transfer member against the convex working face of the body member.

28. A dermatome comprising a body member having a convex working surface rockable on a patient's body; means for securing a flexible graft transfer member, having an adhesive facing, taut against the convex surface, whereby rocking of said body member will progressively lift an area of skin by adhesion of the latter to the taut graft-transfer member; and means for supporting a knife a predetermined distance from the convex surface for cutting movement to that it may progressively cut a graft of the skin as the latter is lifted.

29. A dermatome comprising a body member having a convex surface; means for mechanically temporarily retaining a flexible graft-transfer member, having an adhesive skin-engaging surface, on said convex surface; and means for supporting a graft-cutting member a predetermined distance from the convex surface for cutting movement parallel thereto.
